The ornamental design for a sloped wireless sensor, as shown and described.

DESCRIPTION

FIG. 1 is a perspective view of a sloped wireless sensor; FIG. 2 is a top view of the sloped wireless sensor system of FIG. 1;

FIG. 3 is a bottom view of the sloped wireless sensor system of FIG. 1;

FIG. 4 is a front view of the sloped wireless sensor system of FIG. 1;

FIG. 5 is a rear view of the sloped wireless sensor system of FIG. 1;

FIG. 6 is a left side view of the sloped wireless sensor system of FIG. 1; and,

FIG. 7 is a right side view of the sloped wireless sensor system of FIG. 1.

The broken lines depict unclaimed portions of the wireless sensor and form no part of the claimed design.
